CLAIM

We claim the ornamental design for a template for making decorative ribbons, as shown and described.

DESCRIPTION

FIG. 1 is a perspective view of a template for making decorative ribbons according to my new design;

FIG. 2 is a front view of the template;

FIG. 3 is a rear view of the template;

FIG. 4 is a top plan view of the template;

FIG. 5 is a bottom view of the template;

FIG. 6 is a left side view of the template, a right side view being identical to the left side view;

FIG. 7 is a sectional view of the template taken along lines 7—7 in FIG. 2;

FIG. 8 is a sectional view of the template taken along lines 8—8 in FIG. 2; and,

FIG. 9 is a sectional view of the template taken along lines 9—9 in FIG. 6.
